UNITED STATES PATENT OFFICE.

JOHN W. KERNODLE AND ADAM H. HAUN, OF LEBANON, INDIANA.

IMPROVEMENT IN ASH-LEACHES.

Specification forming part of Letters Patent No. **139,963**, dated June 17, 1873; application filed January 6, 1873.

To all whom it may concern:

Be it known that we, JOHN W. KERNODLE and ADAM H. HAUN, of Lebanon, in the county of Boone and State of Indiana, have invented a new and Improved Fire-Proof Ash-Leacher or Lye-Barrel; and we do hereby declare that the following is a full, clear, and exact description of the same, reference being had to the accompanying drawing forming a part of this specification:

The invention relates to means for the leaching of ashes so as to secure the lye without danger of fire, and consists in a metallic covered cylinder, scalloped at the lower end to allow the lye of ashes to flow therefrom, and a metallic inclined trough upon which it rests, and by which the lye is conveyed to a suitable receptacle.

The drawing is a vertical sectional elevation. A represents the inclined trough, having the vertical flange B therearound, the legs C, and the discharge-spout D. E is the cylinder, scalloped at H around its lower edge, and having the cover F, provided with a handle, G.

The application to its intended use is as follows:

This device may be placed at any convenient place in the house or an out-building thereof, so as to receive the hot ashes as they are taken from the fires. Being of metal and raised out of contact with any combustible, there is no danger of generating a fire. The ashes being wetted in the usual manner, the liquid percolates slowly and gradually through them, absorbs the alkali, carries it through the scallops H, along the trough A B, and out at the discharge D, into a receptacle prepared to receive it.

Having thus described our invention, what we claim as new, and desire to secure by Letters Patent, is—

The ash-leacher, consisting of cylinder E, scalloped at H, cover F G, and trough A B D, all arranged as described.

JOHN W. KERNODLE
ADAM H. HAUN.
